BURNISHING TOOL

Alfred E. Comstock, Detroit, Mich., assignor to
The Murray Corporation of America, Detroit,
Mich., a corporation of Delaware

Application October 5, 1942, Serial No. 460,833

7 Claims. (Cl. 29—90)

This invention relates to burnishing tools, and particularly to a tool for burnishing the scratch marks which may be present in a surface of a sheet of material.

In the copending applications of R. D. Stephens, Serial No. 459,417, filed Sept. 23, 1942, and Alfred H. Haberstump, Serial No. 460,319, filed Sept. 30, 1942, and assigned to the assignee of the present invention, burnishing tools are illustrated, described and claimed, over which the present tool is an improvement.

The tools of the above-mentioned copending applications employ a segmental spherical tip driven in rotation and moved along the scratch marks to iron the metal at the sides of the mark into the bases of the mark and into abutted relation to close and seal the mark. The Haberstump application includes friction wheels which prevent any oscillating movement from being transmitted from the burnishing tip to the tool proper and which guides the tool along the scratch mark. A lubricating roller is employed adjacent to the tip for lubricating the metal of the scratch mark and also the tip to prevent the wearing of the tip and the over-working and tearing of the metal. The tearing of the metal also occurs when too great a pressure is applied to the tool for forcing the tool into contact with the metal to be burnished.

The present invention pertains to the use of a spring-pressed burnishing tip by which the amount of pressure applied between the tip and the surface of the sheet is regulated. Stops are provided on the wheel bracket which prevents the spring from becoming solid. A predetermined spring pressure is always applied between the tip and the metal to be burnished and the over-working of the metal through the application of too much pressure is thereby overcome. The invention also pertains to the use of an oil wick directly adjacent to the burnishing tip for concentrating the lubricant directly to the scratch mark and the tip during the burnishing operation.

Accordingly, the main objects of this invention are: to provide a spring-pressed tip on a burnishing tool for regulating the pressure of engagement between the tip and the metal to be burnished; to mount the stem of a burnishing tip in a sleeve having a slot in which a pin in the stem projects for securing the stem within the sleeve while permitting limited movement against a spring provided in the sleeve; to provide a lubricating wick directly adjacent to the burnishing tip for lubricating the area of engagement

between the tip and metal being burnished; and in general, to provide a burnishing tool which is positive in operation and economical of manufacture.

Other objects and features of novelty of the invention will be either specifically pointed out or will become apparent when referring, for a better understanding of the invention, to the following description taken in conjunction with the accompanying drawing, wherein:

Figure 1 is a view in elevation of a burnishing tool, illustrating features of this invention, with the burnishing tip spaced from the material to be burnished;

Fig. 2 is an end view in elevation of the tool illustrated in Figure 1;

Fig. 3 is a broken view of structure similar to that illustrated in Figure 1, with the burnishing tip in contact with the metal to be burnished;

Fig. 4 is an enlarged sectional view of the structure illustrated in Fig. 2, taken on the line 2—2 thereof.

The burnishing tool of the present invention is employed primarily for burnishing scratch marks which are present on the surface of the "Alclad" sheets. These are sheets made of aluminum alloy having a layer of pure aluminum thereon. The aluminum prevents deterioration and oxidation of the core portion and, when scratches are made on the face of the sheet the core metal is exposed. The tip of the present tool is mounted in off-center relation to the driving shank for the purpose of working the metal at each side of the mark into the base of the mark and into sealed relation with each other.

The tool embodies the motor portion 10, the driven chuck or collet 11 in which the tool 12 is secured. A bracket 13 is secured to the housing of the motor portion by a cap 14 and bolts 15. A wheel supporting bracket is secured by a shaft 17 to the bracket 13 and is provided with tabs 18 which abut against the bracket 13 to limit the upward movement of the wheel supporting portion 19. A spring 21 is secured to the end 22 of the bracket 16 and to the bracket 13 for moving the end 22 upwardly and the wheels 24 downwardly.

The end portion 19 of the bracket 16 supports a pair of wheels 24 between arms 25 and 26, which are spaced and disposed on opposite sides of the tool 12. The wheels are supported on pins 27 and extend below the end of the tool 12, when in inoperative position, as illustrated in Figure 1.

Between the arms 26 of the bracket 19 a tubu-

lar element 28 is mounted on an arm 29 on which it is secured by a nut 31. A wick 32, of felt or other similar material, is secured within the end of the tube in which a lubricating material 33 is provided for maintaining the wick saturated.

The tool 12 comprises a sleeve 34 in which the stem 35 of a segmental spherical tip 36 is mounted, with the axis of the stem offset from that of the tip. A pin 37 projects from the stem 35 into slots 38 in the sleeve, for limiting the outward movement of the stem while permitting it to move inwardly within the sleeve. A spring 39 urges the stem outwardly of the sleeve and provides a predetermined pressure on the tip to regulate the force of contact with the surface being burnished.

When a scratch mark in a sheet 41 is to be burnished, the wheels 24 are disposed equi-distant on each side of the mark and the motor portion 10 is moved downwardly to have the tip 36 contact the mark. The stop tabs 18 contact the bracket 13, as illustrated in Figure 3, and limit the downward movement of the driving portion 11 of the tool to prevent the pressure from being directly applied to the tip 36. The maximum pressure on the tip will be that exerted by the spring 39 which will be sufficient to produce the burnishing operation without unduly working the metal being burnished. The wick 32 will be disposed directly adjacent to the tip when the tip contacts the surface, as illustrated in Figure 3, and will lubricate the metal and tip as the burnishing operation progresses.

The flow of air through the conductor 42 of the motor portion 10 of the tool is controlled by the pivoted arms 43 which actuates a plunger 44 of a control valve, (not shown). As the eccentric tip 36 is rapidly rotated on the center line of the scratch mark the wheels 24 stabilize the device and guide the tip as the device is moved backward and forwardly along the mark. The wheels limit the downward movement of the tip to prevent the direct application of pressure thereto.

What is claimed is:

1. A burnishing tool including a tip having a segmental spherical end portion and a shank portion, the axis of the end portion being offset from that of the shank portion which passes through the end portion, a sleeve supporting said shank portion, and a spring urging said shank portion outwardly of the sleeve, and means for driving said shank in rotation.

2. In a device for burnishing the surface of a material including, in combination, a driven element, a burnishing tool supported by said element, said tool embodying a burnishing tip having limited outward movement, a spring for urging said tip downwardly, a bracket, a wheel

supporting arm on said bracket, a wheel on said arm, and stop means for limiting the movement of the wheel supporting arm on said bracket for limiting the relative movement between the burnishing tip and wheel for controlling the pressure applied by the spring to said tip.

3. In a burnishing tool, a driving portion, a portion driven in rotation thereby, a burnishing tool supported by said driven portion having a shank and a burnishing tip axially offset from the shank which is of less diameter than said tip, a spring-pressed wheel disposed adjacent to said burnishing tip, and a tubular element containing a lubricant and a wick supported adjacent to said wheel.

4. In a burnishing device, a driving portion, a driven portion, a burnishing tool rotated by said driven portion, said burnishing tool having a burnishing tip, the axis of which is offset from the axis of rotation of said driven portion, a bracket, an arm pivoted on said bracket, a wheel supported on said bracket so as to be disposed below the tip of said burnishing tool, and a tubular element supported by said arm containing a lubricant and a wick aligned with said tip and disposed adjacent thereto when the tip is moved downwardly relative to said wheels to be in contact with the surface to be burnished.

5. In a burnishing device, a driving portion, a driven portion, a tool supported by said driven portion comprising a tubular element in which the shank of a burnishing tip is secured for limited movement when urged outwardly of the sleeve by a spring, a bracket supported on said device, a spring-pressed wheel disposed adjacent to said tip, a spring for urging said wheel below said tip, and a stop element for limiting the upward movement of said wheel relative to said tip to prevent the application of the applied pressure directly to said tip.

6. In a burnishing tool, a driven portion, a portion for driving said driven portion in rotation, a spring-pressed tip rotated by said driven portion with the axis of the tip in off-center relation to the axis of the driven portion which latter axis falls within the tip, and means for limiting the downward movement of said tip when contacting the surface of a sheet of metal to be burnished.

7. In a burnishing tool, a driven portion, a portion for driving said driven portion in rotation, a spring-pressed tip rotated by said driven portion with the axis of the tip in off-center relation to the axis of the driven portion, means for limiting the downward movement of said tip when contacting the surface of a sheet of metal to be burnished, and a wick containing a lubricant disposed adjacent to said tip when contacting said surface.
